CHAIR

Morton Pearlstine, Bala Cynwyd, Pa., assignor to
Bunting Glider Company, Philadelphia, Pa., a
corporation of Pennsylvania

Application September 21, 1951, Serial No. 16,697

Term of patent 14 years

(Cl. D15—1)

To all whom it may concern:

Be it known that I, Morton Pearlstine, a citizen of the United States, and a resident of Bala Cynwyd, county of Montgomery, State of Pennsylvania, have invented a new, original, and ornamental Design for a Chair, of which the following is a specification, reference being had to the accompanying drawing, forming a part thereof, wherein:

Figure 1 is a front elevational view of a chair, showing my new design; and

Figure 2 is a side elevational view thereof.

Fig. 3 is an enlarged fragmentary view showing the ornamentation of a corner of the back panel.

The characteristic features of the present design reside in the portions shown in full lines in the drawing.

In the design as shown, the seat panel is of

the same design as that of the seat back panel.

I claim:

The ornamental design for a chair, substantially as shown and described.

MORTON PEARLSTINE.
